UNITED STATES PATENT OFFICE

2,078,337

ARTICLE OF MANUFACTURE, FOR
EXAMPLE INSOLESFrank W. Merrick, Boston, Mass., assignor to
United Shoe Machinery Corporation, Paterson,
N. J., a corporation of New Jersey

Application June 30, 1934, Serial No. 733,182

11 Claims. (Cl. 36—22)

This invention relates to articles of manufacture in which strips are sewed edgewise to sheets and is illustrated herein as exemplified by an insole having strips so attached thereto as to provide 5 ribs to which a shoe upper may be secured.

Objects of the invention are to provide articles of manufacture comprising sheets having strips upstanding from the surfaces thereof and more particularly to provide inexpensive insoles for 10 shoes having strips projecting from the surfaces thereof sufficiently to receive a securing means for attaching the uppers to the insoles during the lasting operation.

In one aspect the invention consists in an 15 article of manufacture comprising a sheet having a thin strip placed edgewise thereon and a line of stitching the stitches of which extend through the strip from edge to edge and through the sheet. In a further aspect the invention comprises an insole having a strip projecting from 20 the surface thereof sufficiently to receive the securing means for attaching an upper to the insole during the lasting operation, said strip being secured to the insole by stitches which extend through the insole and from edge to edge 25 through the strip. As illustrated, one edge face of the strip may be beveled to cause the strip to be inclined toward the median line of the insole.

These and other aspects of the invention will 30 appear more fully from the following description when read in connection with the accompanying drawing and will be pointed out in the appended claims.

In the drawing:—

35 Figure 1 is a plan of the "top" side of an insole with the attached upper securing strips according to the invention;

Figs. 2 and 2A are sections, on an enlarged scale, on the lines 2—2 and 2A—2A respectively 40 of Fig. 1;

Fig. 2B illustrates an insole with a modified form of strip, and corresponds to a section on the line 2—2 of Fig. 1;

Fig. 2C is a transverse cross-section of the 45 strip according to Fig. 2B before it is applied to the insole;

Figs. 3 and 4 are sections through the shoe and last, corresponding to the sections on the line 2—2 of Fig. 1, illustrating steps performed in 50 the method of making the shoe;

Fig. 3A is a fragmentary section, corresponding to Fig. 3, showing the modified form of insole and strip according to Figs. 2B and 2C;

According to one form of the invention, the 55 insole 1 has secured thereto, at opposite sides

thereof, strips 3 of suitable material such as leather, or leather substitute such as paper compositions and the like, these strips being of relatively small size, for example, but without limitation thereto, in the order of $\frac{1}{16}$ " thick and from $\frac{1}{8}$ to $\frac{1}{16}$ " high. If desired, the insole may comprise a heel and shank stiffener which as shown is in the form of a thin sheet 4 of fiber board or the like cemented or otherwise secured to the main portion of the insole before applying the 10 strips.

As illustrated by Figs. 1, 2 and 3, the strips are of rectangular cross-section and are placed edgewise against the insole and are sewed thereto by lines of stitching 5, the stitches 1 of which 15 preferably pass through the insole and from edge to edge through the strip. By this construction rigid abutments are formed for enabling an upper 9 to be drawn over a last 11 and to be secured to the abutments by staples or other securing 20 means 13.

In the form of the invention illustrated by 25 Figs. 2B and 2C the strips 3 are inclined inwardly from the edges of the insole, which construction may be desirable to facilitate the stapling operation when employing certain forms of 30 stapling instrumentalities. For this purpose the edges 8 of the strips contacting with the insole surface are beveled. The strips may be held normally to the insole during the sewing operation and when sewed the tension of the stitches acts to draw the strips into their inclined positions illustrated.

Before the upper is worked into lasted position 35 and secured to the strip 3, forming the insole rib, for example, by staples or the like, cement may be applied to the portion of the insole between its edges and the strips 3, or to the corresponding portions of the uppers, or both, the staples holding the uppers in place until the cement dries. This cementing operation may be facilitated, if desired, by subjecting to pressure that portion of the uppers which overlaps the insole. After the uppers are cemented in position, as indicated in Figs. 3 and 3A, the strips 3 and excess 40 portions of the uppers may be severed by a trimming operation, leaving the shoe in the condition illustrated by Fig. 4 preparatory to applying the sole. The method of utilizing my novel insole may be substantially as described in Letters 45 Patent of the United States No. 1,932,545, granted 50 October 31, 1933, on an application of George Goddu.

It will be observed that the stitches passing 55 through the strips edgewise, being under ten-

sion and of considerable diameter relative to the thickness of the strips, draw the latter tightly against the insole to form a substantially rigid abutment, which eliminates all substantial tendency of the abutment to bend or tilt during the operation of applying the uppers. Thus is avoided the common defect of prior constructions.

It will also be understood that the invention is not limited to insoles or shoes, but comprehends any construction in which a strip is sewed edgewise to a sheet or other shape.

The machine for making my novel insole originally disclosed herein is being disclosed and 15 claimed in the divisional application Serial No. 97,839, filed August 25, 1936.

Having described the invention, what I claim as new and desire to secure by Letters Patent of the United States is:

20 1. An article of manufacture comprising a sheet having projecting therefrom a relatively thin strip, an edge of which latter lies against said sheet, and a line of stitching, the stitches of which extend through said sheet and from 25 edge to edge through said strip for securing the latter to said sheet.

2. An article of manufacture comprising a sheet having a relatively thin strip projecting therefrom with an edge of said strip against 30 said sheet, the height of said strip being not less than its thickness, and a line of stitching, the stitches of which extend through said sheet and from edge to edge through said strip for securing the latter to said sheet.

35 3. An article of manufacture comprising a sheet having a relatively thin strip of quadrilateral cross-section projecting therefrom with an edge of said strip against said sheet, and a line of stitching, the stitches of which extend through said sheet and from edge to edge through said 40 strip for securing the latter to said sheet.

4. An article of manufacture comprising a sheet having projecting therefrom an inclined relatively thin strip, an edge of which latter lies 45 against said sheet, and a line of stitching, the stitches of which extend through said sheet and from edge to edge through said strip for securing the latter to said sheet.

5. An article of manufacture comprising a sheet having projecting therefrom an inclined relatively thin strip formed with a beveled edge 50 which lies against said sheet, and a line of stitching, the stitches of which extend through said

sheet and from edge to edge through said strip for securing the latter to said sheet.

6. An insole having adjacent its margin a strip 5 projecting above the insole surface sufficiently to receive the securing means for attaching the uppers to the insole during the lasting operation, said strip being secured to the insole by stitches which extend through the insole and from edge to edge through the strip.

7. An insole having adjacent its margin a relatively thin severable strip projecting above the insole surface sufficiently to receive the securing means for attaching the uppers to the insole during the lasting operation, said strip being inclined toward the median line of the insole and being secured thereto by stitches which extend through the insole and from edge to edge through the strip.

8. An insole having a strip projecting from the insole surface with an edge of said strip against 20 said surface, said strip being of sufficient height to receive the securing means for attaching the uppers to the insole during the lasting operation and being secured to said insole by a line of stitching, the stitches of which extend through the insole and from edge to edge through said strip.

9. An insole having means to which the uppers may be secured during the lasting operation comprising a strip of quadrilateral cross-section, the height of which is not less than its width, said strip being sewed to the insole by a line of stitching, the stitches of which extend through the strip and insole from the side of the latter opposite the strip to the remote side of the strip.

10. An insole having a relatively high and thin strip projecting from the insole surface with an edge of said strip against said surface, said strip being adapted to receive the staples for securing the uppers during the lasting operation and being secured to the insole by a line of stitching, the stitches of which extend through said insole and strip from the side of said insole opposite said strip to the remote side of said strip.

11. An insole having projecting therefrom a strip inclined to the insole surface, said strip being formed with a beveled edge in contact with the insole surface, and a line of stitching, the stitches of which extend through said insole and from edge to edge through said strip.

FRANK W. MERRICK.
